UNITED STATES PATENT OFFICE.

JAMES M. WALKER, OF QUILL LAKE, SASKATCHEWAN, CANADA.

COMBINED FIRE AND BURGLAR ALARM.

1,006,608.

Specification of Letters Patent. Patented Oct. 24, 1911.

Application filed October 22, 1910. Serial No. 588,522.

To all whom it may concern:

Be it known that I, JAMES M. WALKER, a citizen of the Dominion of Canada, residing at Quill Lake, in the Province of Saskatchewan and Dominion of Canada, have invented certain new and useful Improvements in Combined Fire and Burglar Alarms, of which the following is a specification, reference being had to the accompanying drawings.

This invention relates to improvements in alarm devices and more particularly to an improved combined fire and burglar alarm system which may be easily installed at a nominal expense in apartment houses or other large buildings.

Another object of the invention resides in the provision of an alarm system of the above described character which is very reliable in its operation and which upon the occurrence of a fire or an attempt to force an entrance into the apartment, will automatically operate a telephone and give the necessary alarm at the fire department or police headquarters.

With the above and other objects in view, the invention consists of the novel features of construction, combination and arrangement of parts hereinafter fully described and claimed, and illustrated in the accompanying drawings, in which—

Figure 1 is a view showing the interior of an apartment, illustrating the manner in which my improved alarm system is installed; Fig. 2 is a section taken on the line 2—2 of Fig. 1, showing the connection of the operating cord to the sashes of a window; and Fig. 3 is a section taken on the line 3—3 of Fig. 1 illustrating the manner in which the device is operated by the opening of a door.

Referring more particularly to the drawing 5 designates a bar or arm pivotally mounted at one end as shown at 6. This 45 arm is normally held in a substantially vertical position by means of a contractile spring 7 one end of which is secured to the arm and the other end to the wall of the apartment or other stationary object. This 50 arm is positioned in convenient relation with respect to a telephone box 8 which has a magneto therein, the magneto shaft extending through the box and having a crank 9 formed on one end. This crank is adapted 55 to be disposed beneath the free end of the arm or bar 5 to maintain the coiled spring

10 which rotates the magneto shaft under tension.

To the free end of the arm or bar 5 one end of an operating cord 11 is secured, said 60 cord passing around pulleys 12 arranged upon the walls of the apartment. This operating cord may be arranged in any desired manner and placed in position where a fire would be most likely to originate. In 65 order to utilize the device as a burglar alarm as well as a fire alarm the cord is extended above the window of the apartment and is drawn downwardly as shown at 12' to provide a loop portion. A resilient U-shaped 70 strip of metal 13 has its ends disposed in staples 14 secured to the upper rail of the lower sash and the lower rail of the upper sash when the sashes are closed. Staples 14' are also secured to the sash frame to receive 75 the ends of the spring plate when it is desired to adjust the sashes. A pulley 15 is arranged upon this spring strip around which the looped portion 12' of the operating cord passes. After passing over supporting pulleys arranged upon the wall, the operating 80 cord is again drawn downwardly to provide a second loop 12'a adjacent to the door D of the apartment. This door carries a key actuated bolt of any ordinary form whereby 85 the same may be securely locked, said bolt being movable into a casing C arranged on the door jamb. A plate 16 is movable through the top of the casing and has a hook 16' therein to receive the locking dog B 90 when the door is locked. A stud 17 is transversely disposed within the casing beneath the locking bolt. This stud is adapted to be engaged by the hook 16' of the trip plate when the door is being constantly opened 95 and closed by persons occupying the apartment thereby maintaining the operating cord taut without releasing the slack therein which would cause the operation of the alarm. The end of the operating cord after 100 the same has been extended around the walls of the apartment is fixed to a drum 18 upon which it is adapted to be wound to take up the slack therein after the spring plate has been connected to the window sashes and 105 the trip member engaged with the door bolt.

In order to regulate the tension of the spring 7, I provide a bolt 19 which is threaded through the pivoted arm 5 and has a head formed on one end to which the end 110 of the spring 7 is secured. It will thus be seen that by adjusting the bolt in the arm

the tension of the spring may be suitably regulated to retract said arm upon the release of either of the trip elements or the burning of the cord.

- 5 From the above the operation of my improved system will be obvious. Should a fire originate in the apartment around the walls of which the operating cord extends, the cord will be burned through which will permit 10 the spring 7 to retract, thereby drawing the cord around the pulleys arranged upon the walls and carried by the trip element connected to the window sashes and engaging the door bolt. This retraction of the spring 15 moves the arm 5 to a vertical position thereby releasing the spring 10 which immediately rotates the magneto shaft to generate the electric current and ring the bells at the other end of the telephone line, thus notifying 20 the fire department of the presence of fire in the building. The same action takes place should any one attempt to force an entrance into the apartment by opening the window sashes, the movement of said sashes 25 disengaging the end of the spring trip plate and releasing the lowered portion of the operating cord thus permitting the spring 7 to retract. If forcible entry is attempted by means of the door, when the locking bolt 30 is operated to unlock the door it will be moved out of the notch 16 in the trip plate thus permitting the operating cord to be drawn through the various pulleys and the arm 5 elevated to cause the operation of the 35 telephone and notify the police department with which the telephone is connected.

From the foregoing it is believed that the manner in which the various parts are arranged for the performance of their several functions will be apparent. The device is very reliable and efficient in practical operation and by its use attempted burglary is frustrated and the destruction of the building by fire is prevented. It will of 45 course be obvious that the operating cord

may be extended exteriorly of the apartment and to the other parts of the building, or each of the rooms or apartments may be provided with a separate cord, and the telephones connected in circuit with a main 50 telephone which is operated from any one of the apartments giving the alarm.

While I have shown and described the preferred construction and arrangement of the various parts, it will be understood that 55 the device is susceptible of considerable modification without departing from the essential feature or sacrificing any of the advantages of the invention.

Having thus described the invention what 60 is claimed is:—

The combination with a telephone having a spring actuated crank to operate the telephone call bell, of a pivotally mounted arm normally engaged with said 65 crank to prevent operation of the call bell, an operating cord connected to said arm and extended over the walls of an apartment, a resilient hook connected to said cord and to the sashes of a window, a 70 hook connected to the operating cord and engaged with the bolt of a door, a drum on which said operating cord is adapted to be wound to hold the same taut, a pin to be engaged by the hook and hold the same out 75 of contact with the door bolt without releasing the cord, the burning of the cord or the disengagement of said hooks from the window sashes or the door bolt slackening the operating cord, and means for elevating 80 the pivoted arm out of contact with said crank whereby the telephone call bell is operated.

In testimony whereof I hereunto affix my signature in the presence of two witnesses. 85

JAMES M. WALKER.
